UNITED STATES PATENT OFFICE.

JAMES STANLEY GILMORE AND WILLIAM DOUGLAS HALL, OF KALAMAZOO, MICHIGAN.

DESIGN FOR A STATUETTE.

45,749.

Specification for Design.

Patented May 12, 1914.

Application filed February 9, 1914. Serial No. 817,689. Term of patent 3½ years.

To all whom it may concern:

Be it known that we, JAMES STANLEY GILMORE and WILLIAM DOUGLAS HALL, citizens of the United States, residing in Kalamazoo, in the county of Kalamazoo and State of Michigan, have invented a new, original, and ornamental Design for Statuettes, of which the following is a specification, reference being had to the accompanying drawings, forming part thereof.

In the drawings Figure 1 shows a front elevation of the statuette showing our design. Fig. 2 shows a rear elevation thereof.

We claim—

The ornamental design for a statuette as shown.

In testimony whereof, we have hereunto subscribed our names.

J. STANLEY GILMORE.
WM. DOUGLAS HALL.

Witnesses:

J. W. CHASE,
F. G. STANLEY.
